UNITED STATES PATENT OFFICE.

RICHARD N. OAKMAN, OF BROOKLYN, NEW YORK.

INCANDESCENT GAS-BURNER.

No. 867,590.

Specification of Letters Patent.

Patented Oct. 8, 1907.

Application filed March 1, 1906. Serial No. 303,652.

To all whom it may concern:

Be it known that I, RICHARD N. OAKMAN, a citizen of the United States, residing at Brooklyn, in the county of Queens and State of New York, have invented 5 certain new and useful Improvements in Incandescent Gas-Burners, of which the following is a specification.

This invention relates to gas burners, particularly adapted for incandescent gas lamps, or for use with mantles which are made incandescent by the combustion 10 of a mixture of gas and air.

The object of my invention is to provide a simplified and improved construction of the parts or devices composing a burner of the Bunsen type and having a pilot tube for igniting the main volume of gas without causing 15 an explosion thereof or other injurious action upon the mantle or chimney at the time of ignition.

One of the special objects of my invention is to provide means for directing the gas, which flows through the regulating valve, in strong vertical streams into 20 the mixing chamber so as to provide for better drawing in air and mixing it with the gas and forcing the mixture to the top of the chamber where it is ignited.

Another object of my invention is to provide devices for admitting gas to the pilot tube burner at the time 25 that the main supply of gas is cut off from the main burner, and to cut off the supply of gas to the pilot tube at the instant that gas is admitted to the main burner, so that when gas is flowing to, and is ignited at the main burner, the pilot light will be extinguished, thereby 30 preventing soiling of the mantle by soot or carbon from the pilot burner while the main burner is lighted. The extinguishment of the pilot burner at this time is desirable since it burns with a yellow flame and might interfere with the brilliant whiteness of the incandescent 35 mantle. It also results in saving some gas which should be admitted to the main burner.

Another object of my invention is to provide improved details of construction by which the burner can be cheaply made and the parts readily assembled 40 and will be durable and effective in operation.

The matter constituting my invention will be defined in the claims.

I will now describe the details of construction and the operation of my improved burner by reference to 45 the accompanying drawings, in which—

Figure 1 represents an elevation of the burner with parts in section. Fig. 2 represents a vertical section of the lower part of the burner on enlarged scale. Fig. 2^a represents a detail view of the air shutter. Figs. 3 and 4 represent, respectively a vertical section and a top view of a cap or thimble. Fig. 5 represents a top view and Fig. 6 a bottom view of a valve-disk. Fig. 7 represents a vertical section of a modification of a cap, valve-disk and connecting parts. Fig. 8 represents a 55 top plan view of a modified cap. Figs. 9 and 10 represent,

respectively a top and bottom view of a slightly modified valve-disk. Figs. 11 and 12 represent vertical sections of the same, Fig. 12 showing a slightly modified construction. Fig. 13 represents a vertical section of a modified construction of a base piece. 60 Fig. 14 represents a top plan view of the same. Figs. 15 and 16 represent, respectively a top view and a bottom view of a modified valve-disk and arm. Figs. 17 and 18 represent vertical sections, respectively on the lines 17 and 18, Fig. 15. Fig. 19 represents a vertical section of a modified tubular bolt. Fig. 19^a represents a cross-section of a bolt, Fig. 19. Fig. 20 represents a section of a modified valve disk. Fig. 21 represents a sectional view of a modified construction. Fig. 22 represents a modified bolt. 65

The burner pillar A is preferably constructed in the form shown in Figs. 1 and 2 with a base 1, having an internally screw-threaded socket 2 and an external screw thread 3, and an annular shoulder 4. The air chamber is preferably constructed of an inverted cone 5 and an upper conical portion 6 having a cylindrical extension 7. The inverted cone 5 and the conical portion 6 may be united at their bases by a suitable joint 3^a as shown in Fig. 1, and at such joint there may be connected a downwardly projecting circular flange or curtain 3^b for covering the air-ports as shown. The lower inverted cone 5 is provided with air-ports 8 and with a horizontal elongated opening 9 for receiving a set-screw lever or projecting arm of a valve-disk. Within the inverted cone 5 is placed a close fitting air shutter 10 having openings 11 corresponding to, and adapted to register with the air-ports 8. The air shutter 10 is also provided with a projecting arm or lug 12 for turning the same. An upper mixing chamber 13 having at the top the usual cap 14 and gauze cover may be applied to the cylindrical part 7 of the pillar in a usual and well known manner. Any desired form of basket 15 may be used for supporting the chimney. 90

The base 1 may be made open at both ends and the upper end closed by a removable cap 16 which may rest at its lower edges upon the annular shoulder 4. This cap is preferably provided with a large central opening 17 and with two or more circumferential openings 18, as shown in Figs. 3 and 4. These openings 18 are preferably made elongated and tapering as shown for gradually admitting gas to the mixing chamber 19 of the valve-disk, above, is turned to open them less or more. 95

Upon the cap 16 is seated a thick valve-disk 19 of substantially the same diameter as the cap, and having a central opening 20 and two or three circumferential openings 21 as shown in Figs. 5 and 6.

Though three openings 21 are shown in Figs. 5 and 6 I may use only two of such openings as shown in Figs. 9 and 10. These openings 21 are comparatively wide 110

at the base or under side of the disk 19 and are tapered upward to the upper surface of the disk as shown in Figs. 2, 11 and 12. This shape and elongated form of gas opening is important for causing the currents of gas which are passed through the openings in the cap to be straightened upward and discharged in strong vertical streams into the upper mixing chamber, producing the desired Bunsen effect. These gas openings in the disk 19 may be tapered as shown in Fig. 11 or may be made 10 as shown at 21^a, Fig. 12, with a larger cylindrical bore at the base, then a tapered portion to the smaller cylindrical bore passing through the top of the disk. The disk 19 is also provided with a radial horizontal opening or passage 22 for receiving the set-screw lever 23 as shown in Figs. 2 and 7. This set-screw is made with a reduced inner end 23^a where it enters the tubular bolt 25 and with a screw threaded portion 21 which screws into the opening 22, and with an outer knob or head 24. The reduced inner end may have a needlepoint 20 23^b as shown in Fig. 7. This set-screw lever 23 serves to regulate the flow of gas to the pilot tube and for turning the valve-disk 19 upon the cap, also causing the cap and center bolt to turn together. The center bolt 25 is preferably drilled to form a longitudinal bore or passage 27 and is provided at its lower end with a head 26, while the upper end is externally screw threaded to receive the securing nut 30. In assembling the parts a washer 28 is, preferably, placed at the under side of cap 16 and against this washer is placed the spiral 30 spring 29, or any other desired form of spring. The spiral spring 29 bears upon washer 28 and upon the head 26 of the bolt. The upper part of the bore or passage 27 is enlarged for receiving the pilot tube 31 as shown in Figs. 2 and 7. By means of the nut 30 and spring 29 35 the valve-disk 19 will be clamped to the cap 16 so as to prevent leakage of gas but still permitting the disk to be readily turned and adjusted to admit more or less gas through the openings 18 and 21.

As shown in Figs. 2 and 7 a transverse opening is 40 made in the bolt 25 for receiving the reduced end 23^a or 23^b of the set-screw lever 23. Evidently this set-screw can be adjusted to regulate the flow of gas through the pilot tube 31.

In order to provide for shutting gas off from the pilot 45 tube when the main supply of gas is admitted to the main burner the valve-disk 19 may be provided with an angular opening 32 extending vertically from the under face of the disk and then at right angles to the central opening 20 as shown in Fig. 7. When the parts are 50 assembled as here shown the needle-point 23^b of lever 23 will project into the passage 32 for controlling the amount of gas which passes into the pilot tube. In this modified construction I preferably provide two gas openings 18 in the cap and two openings 21 in the disk 55 19 to register therewith for supplying the main burner, and I also provide a third opening 18^a, Fig. 8, in the cap adapted to register with the gas passage 32 in the disk for separately supplying gas to the pilot tube. These openings in the cap and disk 19 will be so placed 60 that when disk 19 is turned to close the openings 18 in the cap the passage 32 will be caused to register with the opening 18^a just before the gas is entirely shut off from the openings 21 in the disk. The arrangement is also such that when the disk 19 is turned to cause the 65 openings 21 to register with the openings 18 in the cap

the passage 32 will be turned away from the opening 18^a and thereby cut off the flow of gas to the pilot burner.

Instead of providing a separate cap 16 as shown in Figs. 2 and 3 I may provide a base 1^a, Fig. 13, which is bored nearly through from the lower end to the upper end, but leaving at the upper end a top plate 16^a which is provided with a central opening for center bolt and with gas openings, as before described. The valve-disk 19^a above the plate 16^a will be made thick as shown in Figs. 17 and 18 and provided with a lateral 70 arm or lever 23^a as an integral part thereof as shown in Figs. 15 and 16. The under side of this disk 19^a is provided with a short indentation or groove 32^a extending radially from the central bolt opening 20^a between the two gas passages 21 as shown in Figs. 16 and 18. In 80 this modified construction the center bolt 25^a is made with two opposite flat sides and is provided with a central bore extending from the upper end to near the middle and having a right angle bore 27^a to its outer surface as shown in Fig. 19. This angular bore or passage 27^a registers with the groove 32^a so as to form a passage way for gas when the groove 32^a is caused to register with the opening 18^a, Fig. 14, in the top plate 16^a, thus supplying gas to the pilot tube which is inserted in the upper end of the center bolt 25^a as previously described. The central opening 20^a in disk 19^a is made with two opposite flat sides to receive the bolt 25^a, having correspondingly flat sides, and cause the same to turn with the disk when it is turned and control the flow of gas either to the main burner or to the 95 pilot burner. This modified construction of parts is simpler and less expensive than the construction shown in Figs. 2 and 7. It will be noticed that in the construction shown in Figs. 7 and 19 the longitudinal bore 27 in the bolt 25 extends downward from the upper 100 end and at right angles but does not extend through the lower end of the bolt. The parts shown in Figs. 13 to 19, inclusive will be assembled substantially like the corresponding parts in Figs. 2 and 7.

Instead of making the valve-disk 19 thick, as shown 105 in Figs. 2, 7 and 11, I may make it of comparatively thin metal as shown at 19^b, Fig. 20, and raise the metal in two places to form tapering conical gas passages 21^b, giving a long travel to the currents of gas and causing them to straighten up and escape in strong vertical 110 streams or currents into the mixing chamber. The comparatively, long tapering passages produce the effect of an injector, causing the gas to pass in strong jets into the mixing chamber, and thereby aid in drawing in the necessary amount of air through the ports 8. 115 The disk-valve may be punched out with an ear or lug 19^c which may be turned up and provided with a screw threaded opening to receive the set screw 23 which may be set up against the nut 30, and serve as a lever to turn the disk-valve 19 or 19^b.

Instead of providing a center bolt with opposite flat sides as shown in Fig. 19^a I may provide a bolt 25^b, Fig. 22, with a circular groove 33 on a line with the angular passage 27^a so that the gas passage 32^a in the disk-valve will always register with this groove and allow gas to pass into the passage-way 27^a and thence to the pilot tube. It will be understood that gas will pass to the pilot tube when the radial groove 32^a registers with the opening 18^a in the cap 16 or in the top plate 16^a in the base 1^a, Figs. 13 and 21.

The parts being assembled, as shown in Fig. 2 or Fig. 7 or Fig. 21, the disk valve is turned so that the gas is first admitted to the pilot tube and lighted at the burner thereof. With the construction shown in Fig. 2, it will only be necessary to turn the set-screw lever 23 so as to open the passage-way 27, thereby permitting gas to flow into the pilot tube. With the construction shown in Fig. 7 the set-screw lever 23 will be adjusted to open the passage-way 32 in the disk valve

10 19, also the passage-way 27, and then the disk valve 19 will be turned to cause the passage-way 32 to register with the opening 18^a in the cap, when gas will flow to the pilot burner and may be lighted. In case of the modified construction shown in Figs. 16, 18 and 21, it 15 will only be necessary to turn the disk valve till the radial groove or channel 32^a registers with the opening 18^a in the cap or top plate 16^a of the base.

The pilot burner being lighted, it will only be necessary to turn the disk valve 19 part of a revolution to 20 admit gas to the main burner. If the disk valve 19 is turned so that its passages 21 register only partly with the elongated openings 18, in the cap 16, that is, so that the disk partly covers the openings 18, a comparatively small flow of gas will pass into the mixing 25 chamber of the burner, and the small streams or currents so passed would be weak and deflected if it were not for the comparatively long and tapering ports or passages 21 in the disk valve. These tapering passages 21 when only partly registering with openings 18 30 straighten up the deflected currents of gas and cause them to shoot upward in strong straight streams into the mixing chamber, producing the desired Bunsen effect and drawing in the requisite proportion of air to the point of ignition. With a rotary disk having the 35 usual straight holes, when the disk is turned to only partly open the holes in the cap, making offsets from one to the other, the currents of passing gas will be diverted in different directions into the mixing chamber and will be so weak that they will not effectively draw 40 in air for making the necessary mixture of gas and air to produce the best results. With my rotary valve disk, having tapering gas ports or passages, this defect is overcome and improved results secured.

It will be understood that with the construction 45 shown in Figs. 7 and 21 the pilot burner will be extinguished so soon as gas is admitted to the main burner and ignited. It is quite important that it be extinguished at this time for the reason that if the pilot burner is left open the flow of gas to the main burner 50 increases the draft in the pilot tube, thereby causing an objectionable long flame at the pilot burner, in other words, the turning on of gas through the main ports and its flow to the main burner lengthens the pilot flame and tends to cool down the blue Bunsen flame 55 within the mantle, also to deposit carbon on the mantle. By providing a pilot burner within the mantle the usual injurious explosions which occur when the gas is ignited are entirely avoided. Ordinarily the flame of the pilot burner is very small and little more 60 than a blue flame so that the amount of gas burned is insignificant. The pilot flame being within the man-

tle is protected from drafts so that it is not liable to be accidentally extinguished.

Having described my invention, what I claim, and desire to secure by Letters Patent, is—

65

1. In an incandescent burner, the combination with the base and a fixed plate at the top thereof having gas ports, of a rotatable valve-disk mounted thereon and having vertically long or extended gas passages adapted to register with said ports in the fixed plate, a tubular center bolt 70 and nut connecting said valve-disk and plate and a set-screw lever engaging with said disk and extending into the passage of the tubular bolt for controlling the flow of gas therethrough, substantially as set forth.

2. In an incandescent burner, the combination with the base and a fixed plate at the top thereof having gas ports, of a rotatable valve-disk thereon and having vertically long tapering ports of greater diameter at the base and adapted to register with said ports in the fixed plate, for causing the passing currents of gas to shoot straight 80 up into the mixing chamber and draw in the desired proportion of air, and a center bolt and nut connecting said disk and plate, substantially as described.

3. In an incandescent burner, the combination with the base and a fixed plate at the top thereof having gas ports, 85 of a rotatable valve-disk thereon and having tapering gas passages adapted to register with the ports in the fixed plate, a tubular center bolt and nut connecting said valve-disk and plate, a pilot tube connecting with said bolt and a set-screw lever engaging with said valve disk and entering the tubular bolt for controlling the flow of gas to the pilot tube, substantially as described.

4. In an incandescent burner, the combination with the base and a fixed plate at the top thereof having ports for admitting gas to the main burner and a separate port for admitting gas to the pilot tube, of a rotatable valve-disk thereon having gas passages therethrough, adapted to register with said ports in the fixed plate, also having a passageway leading to the center, a center bolt having a longitudinal bore or passage and a lateral opening therefrom adapted to register with said passageway in the valve-disk, and a pilot tube connecting with the passageway in the center bolt, whereby gas may be cut off from the pilot tube when it is admitted to the main burner, or cut off from the main burner when it is admitted to the pilot 100 tube, substantially as described.

5. In an incandescent burner, the combination with the base and a fixed plate at the top thereof having gas ports for a main burner and a pilot tube, of a rotatable valve-disk thereon having gas passages adapted to register with said ports for the main burner in the fixed plate, also having a passageway from its under side to its center, a center bolt passing through said plate and disk and having a longitudinal gas passage and a lateral passage thereupon adapted to register with said passage in the disk, a set-screw lever having a conical end or needle point entering the longitudinal passage of the bolt and passageway in the disk, substantially as described.

6. In an incandescent burner, the combination with the base and a cap fitted thereon and having elongated gas ports, of a rotatable valve-disk thereon and having tapering gas passages adapted to register with said ports in the fixed plate, a tubular center bolt passing through said cap and disk and having a lower head, a spring between said head and the cap, a securing nut applied to the upper end of said bolt, a pilot tube connecting with the passageway of the bolt and a set-screw lever engaging with the disk and center bolt, substantially as described.

In testimony whereof I affix my signature in presence of two witnesses.
